UNITED STATES PATENT OFFICE.

OSCAR FERN, OF NEWBURYPORT, MASSACHUSETTS, ASSIGNOR OF ONE-THIRD TO BENJAMIN F. POOR AND ONE-THIRD TO GEORGE P. POOR, BOTH OF NEWBURYPORT, MASSACHUSETTS.

SOLE-GOUGING DEVICE.

1,247,519.

Specification of Letters Patent. Patented Nov. 20, 1917.

Application filed March 5, 1917. Serial No. 153,213.

To all whom it may concern:

Be it known that I, OSCAR FERN, a citizen of the United States of America, and a resident of Newburyport, in the county of Essex and Commonwealth of Massachusetts, have invented certain new and useful Improvements in Sole-Gouging Devices, of which the following is a specification.

This invention relates to devices for gouging out portions of a shoe sole to form a recess in its bottom for the insertion therein of a rubber pad, and it has for its object the production of a device of this character which will be simple in construction and which may be easily operated.

The invention consists in a holder to which shoe soles may be clamped, said holder having a removable plate therein provided with an opening therethrough which serves as a guide for the revoluble cutting tool performing the gouging operation whereby the recesses formed in the bottoms of the shoe soles will always be of the desired shape.

The invention further consists of certain novel features of construction and arrangement of parts which will be fully understood by reference to the description of the drawings and to the claims hereinafter given.

For the purpose of illustrating the invention, one preferred form thereof is illustrated in the drawings, this form having been found to give satisfactory and reliable results, although it is to be understood that the various instrumentalities of which the invention consists can be variously arranged and organized and that the invention is not limited to the precise arrangement and organization of these instrumentalities as herein shown and described.

Of the drawings:

Figure 1 represents a vertical section of a device embodying the principles of the present invention.

Fig. 2 represents a plan of the shoe sole holder. Fig. 3 represents an inverted plan of the same.

Fig. 4 represents a transverse section on line 4—4 on Fig. 3, and

Fig. 5 represents a section on line 5—5

on Fig. 3, showing the clamp used when the gouging is to be performed on a shoe sole before being embodied in a completed shoe.

Similar characters designate like parts throughout the several figures of the drawings.

In the drawings, 10 is a bearing forming a part of any suitable frame and having mounted therein a revoluble member 11 to which is secured a pulley or sheave 12 by which said member 11 is adapted to be rotated. The member 11 has projecting from the lower end thereof a tubular member 13 in which is mounted a shank 14 of a cutting tool 15. The tubular member 13 and the shank 14 are locked to the revoluble member 11 by means of the set screw 15. Secured to the lower end of the bearing 10 by the set screw 16 is the hub 17 of a work support having a broad annular flange 18 having a flat working face 19 through which extends the working tool 14. A work holder is provided consisting of a U-shaped body portion 20 in which is adapted to be mounted a removable plate 21 having a perforation 22 therethrough the outline of which conforms to the shape of the fore part of a shoe which it is desired to operate upon.

The plates 21 are locked in adjusted position in the holder 20 by means of set screws 23, and these plates may be removed and others substituted therefor having perforations therein of a different size and shape, as desired. To the opposite ends of the holder 20 are secured bail shaped handles 24 by which the holder may be held by the operator with the face of said holder 20 placed against the operating face 19 of the work support 18. The opposite face of the holder 20 is provided with two side bars 25 the inner and opposed edges of which are curved to conform to the edges of the sole of a shoe to be operated upon, the bars 25 having a plurality of slots 26 therein through which extend studs 27 fixedly secured in the holder 20, said studs having their outer ends threaded to receive clamping nuts 28 by which the bars 25 may be locked in adjusted positions.

When a shoe is to be operated upon the fore part of the sole is placed against the

lower face of the plate 21 and the bars 25 are moved against the edges thereof and clamped in adjusted position so that the shoe is held rigidly in the holder. The operator then places the flat face of the holder against the operating face 19 of the work support and with the working tool 14 revolving moves the holder over the flat face 19, permitting the working tool to gouge 10 into the under face of the sole a recess or depression, the outline of which will conform to the opening or perforation 22 in the plate 21.

The operator continues to move the work holder relatively to the working tool 14 until this recess in the sole of the shoe is of an even depth throughout. The manner in which the work and the work holder are held in the hands of the operator is clearly 20 shown in Fig. 1 of the drawings, and needs no further description.

The holder 20 is also provided with threaded openings 29 therethrough into which is adapted to be screwed a locking bolt 30, said 25 bolt extending through slots 31 in the bars 25 and also through slots 32 in the cross member 33 having an inward projection 34 adapted to bear against the lower face of a shoe sole 35 when it is desired to form a recess or depression in a shoe sole before it 30 has been attached to the shoe upper.

This provides a more convenient and simple device for gouging into the bottom of a shoe sole either before or after it has 35 been attached to the upper of a shoe and by which a desired shape of recess or depression may be readily formed in the shoe sole preparatory to placing in said recess a pad of rubber or some other similar resilient 40 material.

It is believed that the operation and many advantages of this invention will be fully understood from the foregoing description.

Having thus described my invention, I 45 claim:

1. The combination of a revoluble cutting tool; a bearing therefor provided with a flat work support through which said tool projects; and a shoe holder adapted to be 50 moved over said work support and provided with an opening therein through which said tool may act upon the sole of said shoe.

2. The combination of a revoluble cutting tool; a bearing therefor provided with a flat work support through which said tool projects; a perforated plate adapted to be 55 moved over said flat work support; and means for clamping a shoe sole to said plate.

3. The combination of a revoluble cutting 60 tool; a bearing therefor provided with a flat work support through which said tool projects; a perforated holder adapted to be moved over said flat work support; and members adjustably mounted on said perfo-

rated holder for clamping a shoe sole to said 65 holder.

4. The combination of a revoluble cutting tool; a bearing therefor provided with a flat work support through which said tool projects; a holder adapted to be moved over 70 said flat work support; a plate carried thereby having an opening therethrough; and means projecting over said plate for clamping a shoe sole thereto.

5. The combination of a revoluble cutting 75 tool; a bearing therefor provided with a flat work support through which said tool projects; a holder adapted to be moved over said flat work support; a plate carried thereby having an opening therethrough; slotted 80 bars projecting over said plate for clamping a shoe sole thereto; studs set in said holder and projecting through the slots in said bars; and clamping nuts therefor.

6. The combination of a revoluble cutting 85 tool; a bearing therefor provided with a flat work support through which said tool projects; a holder adapted to be moved over said flat work support; a removable plate carried thereby having an opening therethrough; means projecting over said plate for clamping a shoe sole thereto; and means for locking said plate to said holder.

7. The combination of a revoluble cutting 95 tool; a bearing therefor provided with a flat work support through which said tool projects; a holder adapted to be moved over said flat work support; a plate carried thereby having an opening therethrough; and bars projecting over said plate for clamping 100 a shoe sole thereto, said bars having curved inner edges adapted to engage the edge of said shoe sole.

8. The combination of a revoluble cutting 105 tool; a bearing therefor provided with a flat work support through which said tool projects; a holder adapted to be moved over said flat work support; a plate carried thereby having an opening therethrough; slotted bars projecting over said plate for clamping 110 a shoe sole thereto; studs set in said holder and projecting through the slots in said bars; and clamping nuts therefor, said bars having curved inner edges adapted to engage the edge of said shoe sole.

9. The combination of a revoluble cutting 115 tool; a bearing therefor provided with a flat work support through which said tool projects; a holder adapted to be moved over said flat work support; a plate carried thereby 120 having an opening therethrough; slotted bars projecting over said plate for clamping a shoe sole thereto; studs set in said holder and projecting through the slots in said bars; clamping nuts therefor; a crossbar secured 125 to said holder and adapted to bear against the face of the sole; and means for adjusting the position of said cross bar.

10. The combination of a revoluble cutting tool; a bearing therefor provided with a flat work support through which said tool projects; a holder adapted to be moved over 5 said flat work support; a plate carried thereby having an opening therethrough; means for retaining a shoe sole in adjusted position in said holder; a cross bar secured to said holder and adapted to bear against the

face of the sole; and means for adjusting 10 the position of said cross bar.

Signed by me at Newburyport, Mass., this 24th day of February, 1917.

OSCAR FERN.
